UNITED STATES PATENT OFFICE

132,494

DESIGN FOR A CAP

Paul M. Maxwell, Manhasset, N. Y., and Wilhelmina J. Russy, Jersey City, N. J., assignors to Hat Corporation of America, Norwalk, Conn., a corporation of Delaware

Application February 17, 1942, Serial No. 105,852

Term of patent 14 years

To all whom it may concern:

Be it known that we, Paul M. Maxwell and Wilhelmina J. Russy, citizens of the United States, residing, respectively at Manhasset, county of Nassau, and State of New York, and at Jersey City, county of Hudson, and State of New Jersey, have invented a new, original, and ornamental Design for a Cap, of which the following is a specification, reference being had to the accompanying drawings, forming a part thereof, and in which:

Fig. 2 is a rear view of the cap shown in Fig. 1. Fig. 3 is a side view of the cap shown in Figs. 1 and 2.

Fig. 4 is a top view of the cap shown in Figs. 1, 2 and 3.

We claim:

The ornamental design for a cap, as shown.

PAUL M. MAXWELL.

WILHELMINA J. RUSSY.
